ANTOINE P. PLAUT, OF DETROIT, MICHIGAN, ASSIGNOR OF ONE-HALF TO THE ROBERTS BRASS MANUFACTURING CO., OF DETROIT, MICHIGAN, A CORPORATION OF MICHIGAN.

VACUUM FEED.

Application filed October 22, 1921. Serial No. 509,758.

The invention relates to vacuum feeding apparatus, such, for instance, as is used in connection with motor vehicles for elevating the liquid fuel from the main tank or reservoir. It is the object of the invention to obtain an increased vacuum where the engine is operating under open throttle. To this end the invention consists in the construction as hereinafter set forth.

10 In the drawings:

Figure 1 is a diagram showing a vacuum feeding system, to which my improvement is applied;

Figure 2 is a section through the connecting feeding system;

Figure 3 is a plan view thereof;

Figure 4 is a sectional elevation through a modified connecting feeding system;

Figure 5 is a similar view at right angles 20 to Figure 4.

A is the tank or container, B is the vacuum tank, C the fuel line leading from the tank A to the tank B, D the carburetor, E the fuel feeding line from the vacuum tank 25 to the carburetor, and F the suction line from the manifold G to the tank B. It is usual to merely tap the suction line into the manifold, the suction being produced by the difference between the manifold pressure 30 and atmospheric pressure. This is effective whenever the engine is operating under closed or partially closed throttle, but when the throttle is nearly or completely open, the pressure drop in the manifold is comparatively slight. Consequently, at times there 35 is not sufficient vacuum for the elevation of the fuel.

To increase the vacuum when operating under the conditions just described, I have 40 provided the suction line with a fitting which projects into the manifold to a point near the center thereof, where the velocity of the incoming mixture is greatest. The end of this projection is also fashioned so as 45 to increase the vacuum, preferably by forming a Venturi passage with the suction connection located at the point in the venturi of greatest pressure drop. Thus, as shown in Figures 2 and 3, H is the fitting provided 50 with a nipple I for engaging a threaded aperture in the manifold and the nipple J for attachment to the vacuum conduit. K is an inwardly projecting portion of the fitting which terminates near the center of

the manifold in a portion having a Venturi 55 passage L therethrough. M is a passage connecting the interior of the fitting H with the Venturi passage L and opening into the latter in the throat thereof or at the point where the vacuum will be highest.

With the construction as described, in operation, when the throttle is wide open, the mixture passing through the manifold will be traveling at high velocity, particularly in the center of the stream. This 60 high velocity gas in passing through the Venturi opening L will create an increased pressure drop at the throat thereof, which is communicated through the passage M to the fitting H and the suction conduit connected therewith. Thus the static pressure within the suction conduit is lower than that within the manifold, which will produce a greater lifting effect upon the liquid 65 fuel.

As shown in the modified construction of Figures 4 and 5, the fitting N upon the manifold O comprises the nipple P for threadedly engaging in the wall of the manifold, the nipple P' adapted to be attached 70 to the vacuum conduit and the inwardly projecting portion or extension P² which terminates near the center of the intake manifold. Q is a transverse passageway in the end of the extension P², this passageway 75 having its axis substantially parallel to the path of direction of the mixture passing through the intake manifold and furthermore, opening into the manifold upon the rear side of the extension Q is an axial 80 passageway in the fitting for placing the passageway Q in communication with the vacuum conduit. As shown in Figure 5, the mixture passing through the intake manifold takes the direction indicated by the 85 flow lines so that at the point R directly in advance of the extension P² of the fitting, there is an area of high pressure, while at the point R' there is an area of low pressure due to the gases being deflected around the extension and forming a pocket immediately in rear thereof. The passageway Q in the fitting extension opens into this 90 low pressure area and as a consequence, suction is communicated to the vacuum tank.

100 105
What I claim as my invention is:
1. In a vacuum feeding system, the combination with an intake manifold having an

aperture therein, of a fitting secured to said manifold and having a cylindrical inner portion insertable through said aperture and extending into said manifold transverse to the direction of flow therethrough, said fitting containing a Venturi passage entirely within the cylindrical inner portion and containing also a suction passage connecting with the throat of said Venturi passage, said Venturi passage having its axis substantially parallel to the direction of current through said manifold.

2. In a vacuum feeding system, the combination with an intake manifold having a threaded aperture therein, of a removable fitting threadedly secured to said manifold and having a cylindrical inner portion insertable through said aperture and extending into said manifold transverse to the direction of flow therethrough, said fitting containing a Venturi passage entirely within the cylindrical inner portion and a suction passage connecting with the throat of said Venturi passage, said Venturi passage having its axis substantially parallel to the direction of flow through said manifold.

3. In a vacuum feeding system the com-

bination with an intake manifold having a threaded aperture therein, of a fitting insertable through said aperture and threadedly engageable with said manifold, said fitting having a cylindrical portion extending into said manifold transverse to the direction of flow therethrough, said fitting being also provided with a Venturi passage extending transversely to the axis of said cylindrical portion and arranged entirely within the peripheral contour thereof, and a suction passage extending longitudinally of said fitting and connecting the throat of said Venturi passage.

4. A vacuum fitting for an intake manifold comprising a threaded portion for engaging said manifold, an axially aligned cylindrical portion of not larger diameter than said threaded portion and containing entirely within the cylindrical contour thereof a Venturi passage arranged transversely to the axis of said cylindrical portion, said fitting being provided with a longitudinal passage connecting with the throat of said Venturi passage.

In testimony whereof I affix my signature.
ANTOINE P. PLAUT.
